United States Patent Office.

THEODORE E. KING, OF PAINESVILLE, OHIO.

Letters Patent No. 65,091, dated May 28, 1867.

IMPROVEMENT IN ELASTIC BUTTON FOR CARRIAGES.

The Schedule referred to in these Letters Patent and making part of the same.

TO ALL WHOM IT MAY CONCERN:

Be it known that I, THEODORE E. KING, of Painesville, in the county of Lake, and State of Ohio, have invented certain new and useful improvements in Adjustable Elastic Buttons; and I do hereby declare that the following is a full and complete description of the same, reference being had to the accompanying drawings, making a part of this specification, in which—

Figure 1 is a view of a portion of a curtain.

Figures 2 and 3 are detached views that will be referred to in the description.

Like letters of reference refer to like parts in the views.

In the drawings, A, figs. 1 and 3, represents a portion of the curtain, and B, fig. 2, the part to which the button is secured. This button consists of the screw C, which is adjustable in the piece B, as indicated; a washer, D, placed on the outside against the piece B. On the neck of the screw, between the head and the washer D, referred to, is the rubber ring D', shown in fig. 2, which is a side view of the same. Fig. 3 represents a portion of curtain, with the button-hole or loop E, which is provided with an eyelet, as represented. By the adjustment of this button, the loop can be made to fit either tight or loose over it, as may be necessary. If it is desired to have the loop fit tight, the screw C can be screwed farther into the piece B, and in this way increasing the diameter of the rubber by pressing it between the washer D above referred to and the head of the screw; or if the loop is to be loose over the button, the screw can be drawn out from the washer, the loop can be placed over the button, and then the screw adjusted; or the loop can be placed on after the screw is adjusted, as desired. In this way the curtain can be fastened either tight or loose by adjusting the screw, as described. When an elastic button-hole is used, it is liable to be stretched out of shape, and thus become too large for the button, when, by having the button-hole made with an eyelet, and the button not only elastic but adjustable, there is no fear of its getting out of place; and if the rubber should wear out, the screw can be screwed up, increasing the diameter of the rubber; or new rubber can be placed on the screw.

What I claim as my improvement, and desire to secure by Letters Patent, is—

1. The adjusting-screw C, in combination with the rubber collar D', arranged in relation to the curtains in the manner and for the purpose substantially as set forth.
2. The rubber collar D', and adjusting-screw C, as arranged, in combination with the button-hole E and curtains, for the purpose and in the manner as described.
